PRINTING DIE AND RETAINING MEANS
THEREFOR

Irving J. Klein, Chicago, Ill.

Application November 1, 1933, Serial No. 696,197

9 Claims. (Cl. 101—376)

This invention relates to improvements in retaining devices for signature dies for multigraphs and the like.

An object of the invention resides in the novel base plate for the signature die.

A further object of the invention is found in the adjustable clamps for retaining the die and its base plate on the drum of a signature attachment or device for multigraphs.

With the above and other objects in view, my invention consists in the novel combination and construction of the various parts and members shown in preferred form in the attached drawing, described in the following specification and particularly pointed out in the appended claims.

Referring to the drawing:

Fig. 1 is a view, in perspective, showing my new and improved die and its supporting base and retaining clamps; one of the clamping members and its retaining screw being shown in detached position.

Fig. 2 is an enlarged cross section.

Fig. 3 is an enlarged cross section through the signature die.

Referring to the die which is generally indicated by 10, the die material consists preferably of two layers A and B of rubber separated by a rubberized canvas or fabric C.

The letters or portions of the signature are formed with sloping or diagonal walls, indicated by E. The lower rubber portion B is cemented to cause same to adhere to a supporting base plate 11.

The base plate 11 is formed to securely retain the die 10 and is preferably of metallic material and arcuate in cross section. The curved cross-sectional form is preferably made with a radius which is greater than the radius of the drum 12 to which it is attachable so that it may be forcibly pressed into perfect fit against the drum 12 and thus prevent any high or low spots which cause distortion in parts of the printing.

The base plate 11 is also formed, on the edges of its two opposite sides, with a plurality of spaced integral prongs 11^A which are bent up to retain between them and the curved body portion, the die 10. Obviously these prongs 11^A may be fabricated in any suitable form or spacing and their number may also be varied, or the opposed edges of the base plate 11 might readily be bent over in the form of a single flange.

The rubber die 10, and its supporting base plate 11 is securely attachable to the curved surface of a cylindrical drum 12 by means of a pair 55 of elongated arcuate retaining plate clamps 13

extending lengthwise on and along the sides of the plate 11.

The cross sectional arcuate form of the clamps 13 is preferably made with a radius which is shorter than the radius of the drum 12 and the two side edges of the clamps 13 are beveled or cut obliquely as at 13^A to afford a larger surface contact of the sides of the clamp plates 13 against the drum 12 and the base plate 11 than would be possible with the corners of square edges of the clamps 13.

The clamps 13 are also made preferably of a resilient metal so that when they are securely tightened to the drum 12 by means of the screws 14 they will be slightly flexed upon the tightening of the screws 14 to thereby impose sufficient pressure along their beveled edges to securely frictionally flex and retain the die plate 11 onto the drum 12.

It will also be noted, that the holes 13^B in the clamps 13 are elongated in a direction to afford crosswise adjustment of the clamps 13 relatively to the die supporting plate 11.

It will also be observed that since the die and its supporting plate 11 is only frictionally held by the clamps 13, such die plate 11 may be readily shifted to provide adjustment thereof longitudinally of the drum 12 by simply loosening the clamp-securing screws 14.

I claim:

1. Printing means for multigraphs and the like, including a printing die of flexible material, a flexible metallic base plate to which said printing die is secured, said base plate having a normal arcuate cross-sectional form and being adapted to be mounted on and to extend longitudinally of a rotary member of the multigraph, the arcuate form of said base plate being formed with a greater radius than the radius of said rotary member, and tightening means for retaining said base plate on said rotary member, said tightening means being adapted upon tightening to exert pressure on said base plate to cause a deflection of the normal arcuate form of said base plate to conform same to the curvature of the surface of said rotary member.

2. Printing means as embodied in claim 1, and including said tightening means comprising a pair of flexible transversely arcuate elongated metallic plates, one side of each of said tightening plates engaging one side of the base plate.

3. Printing means as embodied in claim 1, and including said tightening means comprising a pair of flexible transversely arcuate elongated metallic plates, one side of each of said tightening plates engaging one side of the base plate.

ing plates engaging one side of the base plate, said tightening plates having an arcuate cross-section formed with a radius which is shorter than the radius of said rotary member.

5 4. In a printing mechanism having a cylindrical rotary roller, a printing die mounted on a flexible metallic base plate, said base plate extending longitudinally of and over a portion of said cylindrical roller and having a normally 10 arcuate cross-section the radius of which is greater than the radius of said cylindrical roller, clamping means mounted on said cylindrical roller to retain said base plate, said clamping means engaging the sides of said base plate, and 15 means for exerting pressure on said clamping means for retaining said clamping means on said cylindrical roller and for retaining said base plate flexed to conform to the curvature of the surface of said cylindrical roller.

20 5. In a printing mechanism having a cylindrical roller and printing die mounted on a flexible metallic base plate, said base plate extending longitudinally of and over a portion of said cylindrical roller and having a normally arcuate cross-

25 section the radius of which is greater than the radius of said cylindrical roller, clamping means mounted on said cylindrical roller to retain said base plate, said clamping means comprising a pair of plates having a normally arcuate cross- 30 section the radius of which is shorter than the radius of said cylindrical roller and being arranged for engaging the sides of said base plate, and means for exerting pressure on said clamping means for retaining said clamping means on said 35 cylindrical roller and for retaining said base plate flexed to conform to the curvature of the surface of said cylindrical roller.

6. A support for a printing die of flexible material, said support being adapted to be secured 40 to a curved surface of a cylindrical drum and to extend longitudinally of said drum and comprising a plate of flexible material of a normally arcuate cross-section the radius of which is longer than the radius of said drum, means for 45 retaining the printing die on said plate, and means for retaining said plate on said drum,

said plate being adapted to be flexed in cross-section by pressure of said retaining means to conform to the curvature of the surface of said drum.

7. In clamping means for a printing device 5 having a cylindrical drum and a printing die supported on an elongated flexible metallic plate member of normally arcuate cross-section of a different curvature than the curvature of the surface of said drum, said clamping means comprising a pair of elongated flexible plates of arcuate cross-section, each of said elongated flexible clamping plates having one side in engagement with a side of said die-supporting plate member, and pressure-exerting means for removably securing said clamping plates to said drum and to said die-supporting plate member to thereby flex said die-supporting plate member to conform it to the curvature of the surface of said cylindrical drum.

10 8. In clamping means as embodied in claim 7, and including each of said clamping plates having the two longitudinal side edges thereof formed obliquely to the faces of the plates.

15 9. A unitary printing die adapted to be secured to a cylindrical drum, said printing die including an elongated flexible metallic base plate of normally arcuate cross-section of a different curvature than the curvature of the surface of said cylindrical drum, a printing structure secured to the convex face of said plate and comprising an outer layer of resilient material having printing characters formed on the outer face thereof, a cushion of resilient material mounted adjacent the convex face of said plate, a layer 20 of thin fabric mounted between said outer layer of resilient material and said cushion material, and pressure-exerting means for flexing said plate and said printing structure to conform the curvature of said plate and said printing structure to the curvature of the surface of the cylindrical drum, said pressure-exerting means being adapted to secure the unitary printing die 25 to the drum.
